UNITED STATES PATENT OFFICE

HENRY ANDREWS NEAL, OF RICHMOND, ENGLAND.

CARBURETER FOR INTERNAL-COMBUSTION ENGINES.

1,018,262.

Specification of Letters Patent. Patented Feb. 20, 1912.

Application filed March 7, 1910. Serial No. 547,797.

To all whom it may concern:

Be it known that I, HENRY ANDREWS NEAL, a subject of the King of England, residing at Richmond, in the county of Surrey, England, have invented certain new and useful Improvements in Carbureters for Internal-Combustion Engines, of which the following is a specification.

The present invention relates to carbureters of the multiple jet type and according to the invention both a hand controlled throttle for regulating the amount of mixture supplied to the engine and a suction controlled throttle for controlling the suction at each jet are employed.

The invention will be best understood by reference to the accompanying drawings, in which:

Figure 1 is a perspective view of the carbureter parts being broken away for clearness, Fig. 2 is a longitudinal section through the apparatus, and Fig. 3 is a section on the line 3—3 of Fig. 2.

Like letters represent like parts throughout the drawings.

The liquid fuel is supplied to the jets A in any desired manner, but preferably from an ordinary float-feed chamber B, the liquid passing into the channel C that, as shown in Fig. 2, is common to all the jets of which any desired number may be used, four being shown in the figure. Each jet A extends into a separate channel or choke tube D' formed in the body piece D of the carbureter; the channel or space E being freely open to the atmosphere. Each jet therefore receives its own properly proportioned supply of air from the open channel E into its own particular channel or carbureting chamber D' whence the mixture passes into the mixing chamber F (Fig. 2) and from there to the branch D² which leads to the engine and through which the suction of the engine reaches the jets. The row of jets can be partly or entirely opened or closed by a cylindrical piston valve or throttle G which can be reciprocated by the operator by means of the rod G' connected to any convenient operating device.

At the end of the mixing chamber F is an automatic throttle valve H operating to open or close a port D³ through which all the mixture from F passes into the branch D². The port communicates with an annular recess D⁴ in the wall of the chamber F. The valve H is controlled by a spring H'

and in the drawing is shown as normally retained in its open position. Dashpot action of the valve H to prevent chattering is secured, by the piston portion H² working in the short cylinder J and displacing air or liquid by any convenient means such as openings in the cover or by the piston rod being a loose fit in the cylinder. It will be seen that the section of the cylinder or pocket J adjacent the outlet D³ is reduced or of smaller diameter than the body of said pocket, and the portion or section H² of the valve H is of greater diameter than the body of said valve to fit closely within the enlarged portion of said pocket J. The cylinder J with its end-plate J' serves as a cover to the otherwise open end of the mixing chamber F.

The suction or vacuum acting upon the valve H is that obtaining in the mixing chamber and not that in the engine inlet pipe. At the side of the piston G in a separate chamber K' is a multiple valve K for controlling an auxiliary supply of air. Air-holes K² are formed in the wall of the chamber K' and orifices K³ in the valve K through which when the valve is open extra air can enter the mixing chamber by orifices F', which are opposite to and correspond with the previously mentioned jet channels D'. The channels K³ are opened and closed by the throttle G at the same time and to the same extent as are the carbureting chambers or channels D'. The valve has an operating arm K⁴ for adjusting it.

The operation is as follows:—For starting purposes the throttle G would be moved to unmask the first of the jets A; this would allow a sufficient quantity of explosive mixture to pass into the mixing chamber F, and from said chamber through the port D³ (which when the engine is not working is, as shown in Fig. 2, wide open) and branch D² to the engine. This amount of mixture would be correct as to its proportions of air and fuel and is intended to be sufficient to start the engine and maintain it running quietly. Increased speed being required, the throttle G would be moved farther to the right and unclose the second, third, etc., of the jets. The tendency of the extra suction due to the increased engine speed would be to suck more fuel through each jet and to produce an over-rich mixture, but this tendency is modified by the action of the valve H which would be sucked in against

the pressure of the spring H' and so reduce the area of the port D³ and thereby check the excessive suction. The same action would occur no matter how many of the jets 5 A were uncovered and a correct proportion of fuel and air is thus secured whatever quantity of fuel may be used at any particular moment by the engine.

The object of the valve K is not to vary 10 the proportions of air and fuel in the ordinary working of the engine, but it is provided for the purpose of correcting the mixture obtained from each jet according to the atmospheric conditions; for example, in 15 a dry atmosphere the engine could take a larger proportion of air than in a humid condition of the atmosphere. It follows therefore that the valve K is intended to be set once for all when starting the engine according to the prevailing conditions of the atmosphere and would not need to be altered 20 until those conditions changed.

It will be appreciated that the proportions of the mixture may be varied by altering 25 the loading of the valve H.

What I claim as my invention and desire to secure by Letters Patent is:—

1. In a carbureter for an internal combustion engine, the combination of a mixing 30 chamber having an air inlet channel and a mixture outlet, a carbureting chamber communicating with the mixing chamber, a valve adapted to vary the dimension of the opening between the carbureting and mixing 35 chambers, a second valve for varying the extent of opening of the air inlet channel to the mixing chamber, and a suction-operated throttle controlling the outlet from the mixing chamber.

2. In a carbureter for an internal combustion engine, the combination of a mixing chamber having a plurality of air inlets and a mixture outlet, a plurality of carbureting chambers, an adjustable valve adapted to 40 establish communication between any desired 45 number of the carbureting chambers and the mixing chamber, a second valve controlling the air inlets to the mixing chamber, and a suction-operated throttle controlling the mixture outlet from the mixing 50 chamber.

3. In a carbureter for an internal combustion engine, the combination of a mixing chamber having a mixture outlet and a plurality 55 of carbureting chambers disposed at different points along its length, a valve free to slide in the mixing chamber to establish communication between any desired number of the carbureting chambers and the mixing chamber, and a suction-operated throttle 60 controlling the outlet from the mixing chamber.

4. In a carbureter for an internal combustion engine the combination of, a plurality 65 of fuel jets, a mixing chamber having

an outlet to the engine, a plurality of air-inlet channels whereof different channels are in communication with different jets, a plurality of auxiliary air-inlet orifices situated opposite the main air-inlet orifices, a valve for the mixing chamber that can be moved varying distances to uncover a greater or less number of the channels, a suction operated throttle controlling the outlet from the mixing chamber to the engine, 75 and a valve adjustable for controlling the degree of opening of the auxiliary air inlet orifices, substantially as set forth.

5. In a carbureter for an internal combustion engine, the combination of a mixing 80 chamber having a mixture outlet and a pocket whose longitudinal axis is transverse to the direction of said outlet, a plurality of carbureting chambers that communicate with the mixing chamber, an adjustable 85 valve controlling the communication between the carbureting and mixing chambers, and a suction-operated throttle valve mounted in said pocket of the mixing chamber and adapted to obstruct the outlet from such 90 chamber.

6. In a carbureter for an internal combustion engine, the combination of a mixing chamber having a mixture outlet and a plurality of air inlets, a plurality of carbureting chambers each adapted to communicate with the mixing chamber, an adjustable valve controlling the communication between each of the carbureting chambers and the mixing chamber, a second adjustable valve controlling the air inlets to the mixing chamber, and a plunger mounted in a pocket in the mixing chamber and adapted to be moved by the suction in said chamber to vary the extent of opening of the mixture outlet. 100

7. In a carbureter for an internal combustion engine, the combination of a mixing chamber having a mixture outlet and a plurality of air inlets, a plurality of carbureting chambers each adapted to communicate with the mixing chamber, an adjustable valve controlling communication between each of the carbureting chambers and the mixing chamber, a second adjustable valve controlling the air inlets to the mixing 110 chamber, a plunger mounted in a pocket in the mixing chamber and adapted to be moved by suction in said chamber to vary the extent of opening of the mixture outlet, and a spring surrounding said plunger and 115 acting to maintain it in position where it will not obstruct the mixture outlet.

8. In a carbureter for an internal combustion engine, the combination of a mixing chamber having a mixture outlet and a plurality of air inlets, a plurality of carbureting chambers each adapted to communicate with the mixing chamber, an adjustable valve controlling communication between each of the carbureting chambers and 120

the mixing chamber, a second adjustable valve controlling the air inlets to the mixing chamber, a plunger mounted in a pocket in the mixing chamber and having at one 5 end an enlarged head that bears against the wall of said pocket, said plunger adapted to be shifted by suction in the mixing chamber to project its other end across the mixture outlet, and a spring surrounding the 10 plunger within said pocket and bearing

upon the head thereof and a stationary abutment.

In testimony whereof I have signed my name to this specification in the presence of two subscribing witnesses.

HENRY ANDREWS NEAL.
